(57) **CLAIM**

The ornamental design for an ultrasonic diagnostic equipment, as shown and described.

DESCRIPTION

FIG. 1 is a perspective view of an ultrasonic diagnostic equipment showing our new design;
FIG. 2 is a front view thereof;
FIG. 3 is a rear view thereof;
FIG. 4 is a left side view thereof;
FIG. 5 is a right side view thereof;
FIG. 6 is a top plan view thereof;
FIG. 7 is a bottom plan view thereof;
FIG. 8 is a perspective view of the tray portion thereof shown separately for clarity of the illustration; and,
FIG. 9 is cross sectional view thereof taken along line 9-9 of the FIG. 8.

The broken lines in the drawing views are included for the purpose of illustrating portions of the ultrasonic diagnostic equipment that form no part of the claimed design.
